(57) **ABSTRACT**

A power connector includes an insulating body and a first terminal module. The insulating body has a mating slot configured to receive a mating module. The first terminal module includes a first power terminal and a second power terminal. The first power terminal includes a first main body and a first elastic arm bent back from one end of the first main body. The second power terminal includes a second main body and a first extension arm extending from one end of the second main body. The first elastic arm extends into the mating slot. The first elastic arm is configured to be in direct contact with the mating module. The first extension arm is configured to be electrically connected to the mating module indirectly through the first elastic arm.

POWER CONNECTOR WITH IMPROVED TERMINAL CONFIGURATION

CROSS-REFERENCE TO RELATED APPLICATION

This patent application claims priority of a Chinese Patent Application No. 202310402985.X, filed on Apr. 14, 2023 and titled “POWER CONNECTOR”, the entire content of which is incorporated herein by reference.

TECHNICAL FIELD

The present disclosure relates to a power connector, which belongs to a technical field of connectors.

BACKGROUND

A power connector generally includes an insulating body and a plurality of conductive terminals. When the power connector is used to transmit power, the conductive terminals include a power terminal. The insulating body defines a mating slot. The power terminal includes a mating elastic arm extending into the mating slot.

In the related art, at the initial stage of use of the power terminal, there is a relatively large plugging force between the mating elastic arm and a mating connector, which makes the plugging and unplugging not soft enough. However, after repeated plugging and unplugging, the plugging force decreases, which affects the mating effect between the mating elastic arm and the mating connector. The power terminal includes an inner layer terminal and an outer layer terminal. Both the inner layer terminal and the outer layer terminal need to be made of a material with good elasticity. However, the material with good elasticity generally reduces its ability to conduct electricity, thereby limiting the overall flow capacity.

SUMMARY

An object of the present disclosure is to provide a power connector, which is capable of making plugging and unplugging between the power connector and the mating module relatively soft.

In order to achieve the above object, the present disclosure adopts the following technical solution: a power connector, including: an insulating body defining a mating slot configured to accommodate a mating module; and a first terminal module assembled to the insulating body, the first terminal module including a first power terminal and a second power terminal; the first power terminal including a first main body and a first elastic arm bent back from one end of the first main body; the second power terminal including a second main body and a first extension arm extending from one end of the second main body; the first elastic arm extending into the mating slot; the first elastic arm being configured to be in contact with the first extension arm when the mating module is inserted in the mating slot; wherein the first elastic arm is configured to be in direct contact with the mating module; and the first extension arm is configured to be electrically connected to the mating module indirectly through the first elastic arm.

In order to achieve the above object, the present disclosure adopts the following technical solution: a power connector, including: an insulating body defining a mating slot configured to accommodate a mating module; and a first terminal module including a first power terminal and a

second power terminal; the first power terminal including a first main body and a first elastic arm bent back from a front end of the first main body along a front-to-rear direction; the second power terminal including a second main body and a first extension arm extending from one end of the second main body along a rear-to-front; the first elastic arm extending into the mating slot; the first extension arm being configured to be sandwiched by the first elastic arm and the first main body when the mating module is inserted in the mating slot; wherein the first elastic arm is configured to be in direct contact with the mating module; and the first extension arm is configured to be electrically connected to the mating module indirectly through the first elastic arm.

In the present disclosure, the first elastic arm is in contact with the mating module, and the first elastic arm adopts a folded structure to form multiple elastic deformation points to disperse the plugging and unplugging force. The plugging and unplugging between the mating module and the first power terminal is relatively soft, so that the plugging force between the first elastic arm and the mating module can be kept more stable. The second power terminal is not directly plugged and unplugged with the mating module, which makes it possible for the second power terminal to be made of materials with high conductivity and weak elasticity (without affecting the overall elastic contact reliability), which greatly improves the overall current carrying capacity.

BRIEF DESCRIPTION OF DRAWINGS

FIG. 1 is a structural schematic view of a power connector, a mating module and a circuit board in accordance with an embodiment of the present disclosure;

FIG. 2 is an exploded schematic view of FIG. 1;

FIG. 3 is an exploded schematic view of part of the structure in FIG. 1;

FIG. 4 is a structural schematic view of FIG. 1 from another angle;

FIG. 5 is an exploded schematic view of FIG. 4;

FIG. 6 is a top view of part of the structure in FIG. 1;

FIG. 7 is a schematic cross-sectional view taken along line C-C of FIG. 6;

FIG. 8 is a schematic structural view of an insulating body in FIG. 5;

FIG. 9 is an enlarged schematic view of area A in FIG. 8;

FIG. 10 is a schematic structural view of FIG. 8 from another angle;

FIG. 11 is an enlarged schematic view of area B in FIG. 10;

FIG. 12 is a schematic structural view of a first terminal module and a second terminal module in FIG. 3;

FIG. 13 is a side view of FIG. 12;

FIG. 14 is a schematic structural view of a first power terminal and a second power terminal in FIG. 13;

FIG. 15 is an exploded schematic view of the first power terminal and the second power terminal in FIG. 12;

FIG. 16 is a schematic structural view of the first power terminal and the second power terminal in FIG. 12;

FIG. 17 is an exploded schematic view of FIG. 15 from another angle;

FIG. 18 is a schematic structural view of a third power terminal and a fourth power terminal in FIG. 13;

FIG. 19 is an exploded schematic view of the third power terminal and the fourth power terminal in FIG. 12;

FIG. 20 is an exploded schematic view of the third power terminal and the fourth power terminal in FIG. 12;

FIG. 21 is an exploded schematic view of FIG. 20 from another angle;

FIG. 22 is a schematic structural view of a first signal terminal and a second signal terminal in FIG. 3;

FIG. 23 is a side view of the first terminal module and the second terminal module in accordance with another embodiment of the present disclosure; and

FIG. 24 is a partially enlarged schematic view of FIG. 13.

DETAILED DESCRIPTION

Exemplary embodiments will be described in detail here, examples of which are shown in drawings. When referring to the drawings below, unless otherwise indicated, same numerals in different drawings represent the same or similar elements. The examples described in the following exemplary embodiments do not represent all embodiments consistent with this application. Rather, they are merely examples of devices and methods consistent with some aspects of the application as detailed in the appended claims.

The terminology used in this application is only for the purpose of describing particular embodiments, and is not intended to limit this application. The singular forms "a", "said", and "the" used in this application and the appended claims are also intended to include plural forms unless the context clearly indicates other meanings.

It should be understood that the terms "first", "second" and similar words used in the specification and claims of this application do not represent any order, quantity or importance, but are only used to distinguish different components. Similarly, "an" or "a" and other similar words do not mean a quantity limit, but mean that there is at least one; "multiple" or "a plurality of" means two or more than two. Unless otherwise noted, "front", "rear", "lower" and/or "upper" and similar words are for ease of description only and are not limited to one location or one spatial orientation. Similar words such as "include" or "comprise" mean that elements or objects appear before "include" or "comprise" cover elements or objects listed after "include" or "comprise" and their equivalents, and do not exclude other elements or objects. The term "a plurality of" mentioned in the present disclosure includes two or more.

Hereinafter, some embodiments of the present disclosure will be described in detail with reference to the accompanying drawings. In the case of no conflict, the following embodiments and features in the embodiments can be combined with each other.

Referring to FIGS. 1 to 24, the present disclosure discloses a power connector 100 for mating with a mating module 200. The power connector 100 includes an insulating body 1, a first terminal module 2 mounted to the insulating body 1, a second terminal module 3 mounted to the insulating body 1, and a third terminal module 4 mounted to the insulating body 1.

Referring to FIG. 2, the insulating body 1 defines a mating slot 10 configured to receive the mating module 200. The insulating body 1 includes a mating surface 110, a first mating slot 10a extending through the docking surface 110, and a second mating slot 10b extending through the docking surface 110. The first mating slot 10a and the second mating slot 10b communicate with each other. The mating slot 10 includes the first mating slot 10a and the second mating slot 10b.

Referring to FIG. 5, the insulating body 1 includes a first receiving slot 10c communicating with the first mating slot 10a, and a second receiving slot 10d communicating with the second mating slot 10b. Both the first receiving slot 10c

and the second receiving slot 10d extend through a rear surface 120 of the insulating body 1. Referring to FIG. 8, a first inner plate 11 is disposed in the first receiving slot 10c. The first inner plate 11 divides the first receiving slot 10c into a first sub-receiving slot 101c and a second sub-receiving slot 102c. The first sub-receiving slot 101c is configured to accommodate the first terminal module 2. The second sub-receiving slot 102c is configured to accommodate the second terminal module 3. The first inner plate 11 supports the first terminal module 2. The first inner plate 11 plays a positioning role for the second terminal module 3. The second receiving slot 10d is configured to accommodate the third terminal module 4. Referring to FIG. 8, a second inner plate 12 is disposed in the second receiving slot 10d. The second inner plate 12 divides the second receiving slot 10d into a third sub-receiving slot 101d and a fourth sub-receiving slot 102d. In the illustrated embodiment of the present disclosure, the first sub-receiving slot 101c and the second sub-receiving slot 102c are disposed along a thickness direction of the insulating body 1. The third sub-receiving slot 101d and the fourth sub-receiving slot 102d are disposed along the thickness direction of the insulating body 1.

Referring to FIG. 5, the insulating body 1 includes a top wall 13, a bottom wall 14 opposite to the top wall 13, a first side wall 15 connecting one end of the top wall 13 and one end of the bottom wall 14, and a second side wall 16 connecting another end of the top wall 13 and another end of the bottom wall 14. The top wall 13, the bottom wall 14, the first side wall 15 and the second side wall 16 are located on a periphery of the mating slot 10.

Continuing to refer to FIG. 5, the rear surface 120 of the insulating body 1 includes a first end surface 1201 on the top wall 13, a second end surface 1202 on the first inner plate 11, and a third end surface 1203 on the bottom wall 14. A first distance is formed between the first end surface 1201 and the mating surface 110 of the insulating body 1. A second distance is formed between the second end surface 1202 and the mating surface 110 of the insulating body 1. A third distance is formed between the third end surface 1203 and the mating surface 110 of the insulating body 1. A numerical value of the first distance is greater than a numerical value of the second distance. The numerical value of the second distance is greater than a numerical value of the third distance. That is to say, the top wall 13, the first inner plate 11 and the bottom wall 14 are distributed in steps.

The first terminal module 2 is mounted to the insulating body 1. The first terminal module 2 is at least partially accommodated in the first sub-receiving slot 101c. Referring to FIG. 10, the first terminal module 2 includes a first power terminal 21 and a second power terminal 22. The first power terminal 21 includes a first main body 211, a first elastic arm 212 bent back from one end of the first main body 211, and a first tail portion 213 extending from another end of the first main body 211. The first elastic arm 212 extends into the mating slot 10. The first elastic arm 212 is configured to be in direct contact with the mating module 200.

The first main body 211 and the first elastic arm 212 are integrally formed. Referring to FIG. 11, the first main body 211 includes a first base portion 2111 and a first bent portion 2112 bent from the first base portion 2111. The first tail portion 213 integrally extends from the first bent portion 2112. The first base portion 2111 is of a flat configuration. Referring to FIG. 17, the first base portion 2111 includes a first plate portion 2101 and a second plate portion 2102 connected to the first plate portion 2101. The first plate portion 2101 has a first width W1. The second plate portion

2102 has a second width **W2**. The first width **W1** is greater than the second width **W2**. By narrowing the width of the second plate portion **2102**, a first stepped portion **2103** is formed at a junction of the first plate portion **2101** and the second plate portion **2102**. Referring to FIG. 11, a first abutting platform **1011** is provided in the first sub-receiving slot **101c**. The first stepped portion **2103** abuts against the first abutting platform **1011**. The first abutting platform **1011** plays a role in positioning the first power terminal **21**.

Referring to FIG. 17, the first elastic arm **212** has a third width **W3**. The second width **W2** is equal to the third width **W3**. The first elastic arm **212** is connected to the second plate portion **2102**. The first plate portion **2101** is installed in the first sub-receiving slot **101c**. The second plate portion **2102** extends into the first mating slot **10a**. The first bent portion **2112** extends beyond the first sub-receiving slot **101c**. The first plate portion **2101** is provided with a plurality of first barbs **2104** for holding the first power terminal **21** in the insulating body **1**.

The first elastic arm **212** extends and is bent back from the first base portion **2111**. Specifically, the first elastic arm **212** is formed by bending from the first base portion **2111** and extending toward a direction close to the first bent portion **2112**. The first elastic arm **212** and the first bent portion **2112** are located on a same side of the first base portion **2111** in the thickness direction. As shown in FIG. 13, a first accommodation space **201** is formed between the first main body **211** and the first elastic arm **212**.

Specifically, referring to FIG. 13, the first base portion **2111** has a first surface **211a** and a second surface **211b** which are located on opposite sides along a thickness direction of the first base portion **2111**. The first elastic arm **212** is located on a side where the first surface **211a** is located. Referring to FIG. 15, a first inner surface **212c** of the first elastic arm **212** and the first surface **211a** are located at a periphery of the first accommodation space **201**.

In some embodiments, referring to FIG. 14, the first elastic arm **212** includes a first arc portion **2121**, a first inclined portion **2122**, a first mating portion **2123**, a second inclined portion **2124**, a first abutting portion **2125** and a third inclined portion **2126**. The first arc portion **2121** is connected to the first base portion **2111**. The first inclined portion **2122** is connected to the first arc portion **2121**. The first mating portion **2123** connects the first inclined portion **2122** and the second inclined portion **2124**. The first abutting portion **2125** connects the second inclined portion **2124** and the third inclined portion **2126**. The first inclined portion **2122** is inclined from the first arc portion **2121** to the first base portion **2111**. The second inclined portion **2124** is inclined from the first mating portion **2123** to the first base portion **2111**. However, the degree of inclination of the first inclined portion **2122** is inconsistent with the degree of inclination of the second inclined portion **2124**, so that the first mating portion **2123** protrudes outward relative to the first base portion **2111**, and the entire first elastic arm **212** has elasticity. The third inclined portion **2126** is inclined away from the first base portion **2111** from the first abutting portion **2125**. The first mating portion **2123** is configured to be in contact with the mating module **200**. Utilizing the characteristic of elasticity of the first elastic arm **212**, the contact reliability between the power connector **100** and the mating module **200** is improved. The first abutting portion **2125** is configured to be in contact with the second power terminal **22**.

The first elastic arm **212** adopts a folded structure, and is connected to the first base portion **2111** through the first arc portion **2121**. The first arc portion **2121** can provide an

elastic deformation point, and the first mating portion **2123** can provide another elastic deformation point. Compared with the traditional structure, an elastic deformation point is added to disperse the plugging and unplugging force, reduce the plugging and unplugging resistance, and make the plugging and unplugging relatively soft.

Specifically, referring to FIG. 16, the first mating portion **2123** includes a first arc-shaped surface **212a**. The first arc-shaped surface **212a** is configured to be in contact with the mating module **200**. The first arc-shaped surface **212a** protrudes away from the first surface **211a**. By providing the first arc-shaped surface **212a**, it is beneficial to reduce the scraping of the mating module **200** by the first mating portion **2123**. Referring to the drawings, the first abutting portion **2125** includes a second arc-shaped surface **212b**. The second arc-shaped surface **212b** protrudes in a direction toward the first surface **211a**. The second arc-shaped surface **212b** protrudes in a direction opposite to that of the first arc-shaped surface **212a**.

Referring to FIG. 24, the first arc portion **2121** includes a first inner arc surface **212d**. Along a first direction H-H, a first distance **H1** is formed between the first mating portion **2123** and the first base portion **2111**; a second distance **H2** is formed between the first abutting portion **2125** and the first base portion **2111**; and a third distance **H3** is formed between the first base portion **2111** and the second base portion **2211**. Specifically, the first distance **H1** is equal to the third distance **H3**. The first distance **H1** is larger than a radius of a circle where the first inner arc surface **212d** is located. The radius of the circle where the first inner arc surface **212d** is located is larger than the second distance **H2**. Such arrangement is beneficial to improve the contact reliability between the first abutting portion **2125** and the first contact portion **2222**. At the same time, after the mating module **200** has been plugged and unplugged for many times, it has little effect on the resilience of the first elastic arm **212**, which prolongs the service life of the power connector **100**.

In the illustrated embodiment of the present disclosure, the first terminal module **2** includes a plurality of the first power terminals **21** and a plurality of the second power terminals **22**. The insulating body **1** includes a plurality of first sub-receiving slots **101c**. Each of the first sub-receiving slots **101c** is configured to accommodate one of the first power terminals **21** and one of the second power terminals **22**. Referring to FIG. 9, a third inner plate **17** is provided between two adjacent first sub-receiving slots **101c**. The third inner panel **17** is provided with a first locking slot **171** and a second locking slot **172**. The first side wall **15** located on a periphery of the first sub-receiving slot **101c** is also provided with the first locking slot **171** and the second locking slot **172**. Both the first locking slot **171** and the second locking slot **172** communicate with a corresponding first sub-receiving slot **101c**. The first power terminal **21** is held in the first slot **171**, and the second power terminal **22** is held in the second locking slot **172**, so as to realize the positioning installation of the first power terminal **21** and the second power terminal **22**.

The second power terminal **22** is located on a side of the first surface **211a** of the first base portion **2111**. Referring to FIG. 12, the second power terminal **22** includes a second main body **221**, a first extension arm **222** extending from one end of the second main body **221**, and a second tail portion **223** extends from another end of the second main body **221**. The first extension arm **222** is configured to be electrically connected to the mating module **200** indirectly through the first elastic arm **212**. Specifically, the first extension arm **222**

is configured to be in elastic contact with the first elastic arm 212 so as to realize the electrical connection between the second power terminal 22 and the mating module 200.

In some embodiments, the first extension arm 222 at least partially extends into the first accommodation space 201. The first extension arm 222 abuts against the first elastic arm 212. In another embodiment, a first gap 20a is formed between the first extension arm 222 and the first elastic arm 212 along the first direction H-H. The second arc surface 212b is configured to be in contact with the first extension arm 222. The second arc surface 212b is opposite to the first surface 211a. When the mating module 200 is inserted into the mating slot 10 and inserted in place, the first elastic arm 212 is abutted by the mating module 200 and deformed, so that the first extension arm 222 is in contact with the first elastic arm 212 in the first direction H-H. By forming the first gap 20a between the first extension arm 222 and the first elastic arm 212, the resisting force generated by the first elastic arm 212 on the first extension arm 222 after deformation is reduced. In other embodiments, the first extension arm 222 may also be located outside the first accommodation space 201 and abut against the first elastic arm 212.

The first power terminal 21 adopts a material having the elasticity greater than that of the second power terminal 22. In other words, the elasticity of the metal material used for the first power terminal 21 is greater than that of the metal material used for the second power terminal 22. The hardness of the metal material used by the second power terminal 22 is greater than the hardness of the metal material used by the first power terminal 21. This is because, since the first elastic arm 212 needs to be elastic, it is convenient for the first power terminal 21 to be mated with the mating module 200. The first elastic arm 212 abuts against the first extension arm 222 after being deformed, which requires the first extension arm 222 to increase its hardness, otherwise deformation is likely to occur.

In the illustrated embodiment of the present disclosure, referring to FIG. 13, the second main body 221 includes a second base portion 2211 and a second bent portion 2212 bent from the second base portion 2211. The second tail portion 223 integrally extends from the second bent portion 2212. The second base portion 2211 is flat. The second base portion 2211 is not in contact with the first base portion 2111. Specifically, the second base portion 2211 is spaced apart from the first base portion 2111 along the first direction H-H. The second bent portion 2212 is spaced apart from the first bent portion 2112. The second base portion 2211 is perpendicular to the second bent portion 2212. The first extension arm 222 is located on the side of the first surface 211a.

After the first terminal module 2 is assembled to the insulating body 1, two sides of the first base portion 2111 are locked in the first slot 171, so as to realize the interference fit between the first power terminal 21 and the insulating body 1, and be beneficial to improve the installation stability of the first power terminal 21. Two sides of the second base portion 2211 are locked in the second slot 172, so as to realize the interference fit between the second power terminal 22 and the insulating body 1, and be beneficial to improve the installation stability of the second power terminal 22. The first base portion 2111 is located above the second base portion 2211. A length of the first base portion 2111 along a third direction L-L is greater than a length of the second base portion 2211 along the third direction L-L.

Referring to FIG. 14, the first extension arm 222 includes a first connecting portion 2221 extending from the second base portion 2211 by bending, and the first contact portion 2222 extending from the first connecting portion 2221. The

first contact portion 2222 is configured to be in contact with the first abutting portion 2125. The first contact portion 2222 is closer to the first base portion 2111 relative to the second base portion 2211.

In the illustrated embodiment of the present disclosure, the first contact portion 2222 is in contact with the first base portion 2111. The first contact portion 2222 is flat. The first contact portion 2222 is parallel to the first base portion 2111.

In the illustrated embodiment of the present disclosure, referring to FIG. 15, the first elastic arm 212 includes a plurality of first sub-elastic arms 2120 disposed at intervals along a second direction W-W. The first extension arm 222 includes a plurality of first sub-extension arms 2220 disposed at intervals along the second direction W-W. The number of the first sub-elastic arms 2120 is the same as the number of the first sub-extension arms 2220. The second direction W-W is perpendicular to the first direction H-H. The first direction H-H is the thickness direction of the first base portion 2111. The second direction W-W is a width direction of the first base portion 2111.

The second terminal module 3 is mounted to the insulating body 1. The second terminal module 3 is at least partially accommodated in the second sub-receiving slot 102c. Referring to FIG. 12, the second terminal module 3 includes a third power terminal 31 and a fourth power terminal 32. The third power terminal 31 includes a third main body 311, a second elastic arm 312 extending from one end of the third main body 311 by bending, and a third tail portion 313 extending from another end of the third main body 311. The second elastic arm 312 extends into the mating slot 10. The second elastic arm 312 is configured to be in direct contact with the mating module 200.

The third main body 311 and the second elastic arm 312 are integrally formed. Referring to FIG. 13, the third main body 311 includes a third base portion 3111 and a third bent portion 3112 bent from the third base portion 3111. The third tail portion 313 integrally extends from the third bent portion 3112. Referring to FIG. 21, the third base portion 3111 is flat. The third base portion 3111 includes a third plate portion 3101 and a fourth plate portion 3102 connected to the third plate portion 3101. The third plate portion 3101 has a fourth width W4. The fourth width W4 is greater than the fifth width W5. By narrowing the width of the fourth plate portion 3102, a second stepped portion 3103 is formed at a junction of the third plate portion 3101 and the fourth plate portion 3102. A second abutting platform 1012 is disposed in the second sub-receiving slot 102c. The second stepped portion 3103 abuts against the second abutting platform 1012. The second abutting platform 1012 plays a role in positioning the third power terminal 31.

Referring to FIG. 21, the second elastic arm 312 has a sixth width W6. The fifth width W5 is equal to the sixth width W6. The second elastic arm 312 is connected to the fourth plate portion 3102. The first width W1 is equal to the fourth width W4. The second width W2 is equal to the fifth width W5. The third width W3 is equal to the sixth width W6. The third plate portion 3101 is installed in the second sub-receiving slot 102c. The fourth plate portion 3102 extends into the first mating slot 10a. The third bent portion 3112 extends beyond the second sub-receiving slot 102c. The third plate portion 3101 is provided with a plurality of second barbs 3104 for holding the third power terminal 31 in the insulating body 1.

The second elastic arm 312 extends and is bent back from the third base portion 3111. Specifically, the second elastic arm 312 is formed by bending from the third base portion

3111 and extending toward a direction close to the third bent portion **3112**. The second elastic arm **312** and the third bent portion **3112** are located on different sides in a thickness direction of the third base portion **3111**. As shown in FIG. 13, a second accommodation space **301** is formed between the third main body **311** and the second elastic arm **312**.

Specifically, referring to FIG. 13, the third base portion **3111** has a third surface **311a** and a fourth surface **311b** which are located on opposite sides along a thickness direction of the third base portion **3111**. The second elastic arm **312** is located on a side of the third surface **311a**. The third bent portion **3112** is located on a side where the fourth surface **311b** is located. Referring to FIG. 20, the second inner surface **312c** of the second elastic arm **312** and the third surface **311a** are located at a periphery of the second accommodation space **301**. Referring to FIG. 13, an intermediate plane **S1** is formed between the first surface **211a** and the third surface **311a**. The first elastic arm **212** and the second elastic arm **312** are arranged symmetrically with respect to the intermediate plane **S1**.

In some embodiments, referring to FIG. 18, the second elastic arm **312** includes a second arc portion **3121**, a fourth inclined portion **3122**, a second mating portion **3123**, a fifth inclined portion **3124**, a second abutting portion **3125** and a sixth inclined portion **3126**. The second arc portion **3121** is connected to the third base portion **3111**. The fourth inclined portion **3122** is connected to the second arc portion **3121**. The second mating portion **3123** connects the fourth inclined portion **3122** and the fifth inclined portion **3124**. The second abutting portion **3125** connects the fifth inclined portion **3124** and the sixth inclined portion **3126**. The fourth inclined portion **3122** is inclined from the second arc portion **3121** toward the third base portion **3111**. The fifth inclined portion **3124** is inclined from the second mating portion **3123** toward the third base portion **3111**. However, the degree of inclination of the fourth inclined portion **3122** is inconsistent with the degree of inclination of the fifth inclined portion **3124**, so that the second mating portion **3123** protrudes outward relative to the third base portion **3111**, and the entire second elastic arm **312** has elasticity. The sixth inclined portion **3126** is inclined from the second abutting portion **3125** to a direction away from the third base portion **3111**. The second mating portion **3123** is configured to be in contact with the mating module **200**. The second elastic arm **312** has a characteristic of elasticity to improve the contact reliability between the power connector **100** and the mating module **200**. The second abutting portion **3125** is configured to be in contact with the fourth power terminal **32**.

The second elastic arm **312** adopts a folded structure, and is connected to the third base portion **3111** through the second arc portion **3121**. The second arc portion **3121** can provide an elastic deformation point, and the second mating portion **3123** can also provide an elastic deformation point. In the embodiment shown in the present disclosure, the second elastic arm **312** forms a plurality of elastic deformation points, so that the plugging and unplugging force is dispersed, the plugging and unplugging resistance is reduced, and the plugging and unplugging between the second elastic arm **312** and the mating module **200** is relatively soft.

Specifically, referring to FIG. 19, the second mating portion **3123** includes a third arc-shaped surface **312a** configured to be in contact with the mating module **200**. The third arc-shaped surface **312a** protrudes away from the third surface **311a**. By providing the third arc-shaped surface **312a**, it is beneficial to reduce the scraping of the mating module **200** by the second mating portion **3123**. Referring to

FIG. 20, the second abutting portion **3125** includes a fourth arc-shaped surface **312b**. The fourth arc-shaped surface **312b** protrudes toward a direction close to the third surface **311a**. The fourth arc surface **312b** and the third arc surface **312a** protrude in opposite directions.

Referring to FIG. 24, the second arc portion **3121** includes a second inner arc surface **312d**. Along the first direction H-H, a fourth distance **H4** is formed between the second mating portion **3123** and the third base portion **3111**; a fifth distance **H5** is formed between the second abutting portion **3125** and the third base portion **3111**; and a sixth distance **H6** is formed between the third base portion **3111** and the fourth base portion **3211**. Specifically, the fourth distance **H4** is equal to the sixth distance **H6**. The fourth distance **H4** is larger than a radius of a circle where the second inner arc surface **312d** is located. The radius of the circle where the second inner arc surface **312d** is located is greater than the fifth distance **H5**. Such arrangement is beneficial to improve the contact reliability between the second abutting portion **3125** and the second contact portion **3222**. At the same time, after the mating module **200** has been plugged and unplugged for many times, it has little effect on the resilience of the second elastic arm **312**, which prolongs the service life of the power connector **100**.

The first mating portion **2123** of the first power terminal **21** and the second mating portion **3123** of the third power terminal **31** are spaced along the first direction H-H. The first arc-shaped surface **212a** of the first mating portion **2123** is opposite to the third arc-shaped surface **312a** of the second mating portion **3123**, and the protruding directions are opposite.

In the illustrated embodiment of the present disclosure, the second terminal module **3** includes a plurality of third power terminals **31** and a plurality of fourth power terminals **32**. The insulating body **1** includes a plurality of the second sub-receiving slots **102c**. Each of the second sub-receiving slots **102c** is configured to accommodate one of the third power terminals **31** and one of the fourth power terminals **32**. Referring to FIG. 9, a fourth inner plate **18** is provided between two adjacent second sub-receiving slots **102c**. The fourth inner panel **18** is provided with a third locking slot **181** and a fourth locking slot **182**. The first side wall **15** located on a periphery of the second sub-receiving slot **102c** is also provided with the third locking slot **181** and the fourth locking slot **182**. Both the third locking slot **181** and the fourth locking slot **182** communicate with a corresponding second sub-receiving slot **102c**. The third power terminal **31** is held in the third slot **181**, and the fourth power terminal **32** is held in the fourth locking slot **182**, so as to realize the positioning installation of the third power terminal **31** and the fourth power terminal **32**.

The fourth power terminal **32** is located on the side of the third surface **311a** of the third base portion **3111**. Referring to FIG. 13, the fourth power terminal **32** includes a fourth main body **321**, a second extension arm **322** extending from one end of the fourth main body **321**, and a fourth tail portion **323** extending from another end of the fourth main body **321**. The second extension arm **322** is configured to be electrically connected to the mating module **200** indirectly through the second elastic arm **312**. Specifically, the second extension arm **322** is configured to be in elastic contact with the second elastic arm **312** so as to realize the electrical connection between the fourth power terminal **32** and the mating module **200**.

In some embodiments, the second extension arm **322** at least partially extends into the second accommodation space **301**. The second extension arm **322** abuts against the second

11

elastic arm 312. In another embodiment, as shown in FIG. 23, a second gap 30a is formed between the second extension arm 322 and the second elastic arm 312 along the first direction H-H. The fourth arc surface 312b is configured to be in contact with the second extension arm 322. The fourth arc surface 312b is opposite to the third surface 311a. When the mating module 200 is inserted into the mating slot 10 and inserted in place, the second elastic arm 312 is abutted by the mating module 200 and deformed, so that the second extension arm 322 is in contact with the second elastic arm 312 in the first direction H-H. The second gap 30a is formed between the second extension arm 322 and the second elastic arm 312, so that the resisting force generated by the second elastic arm 312 on the second extension arm 322 after deformation is reduced. In other embodiments, the second extension arm 322 may also be located outside the second accommodation space 301 and abut against the second elastic arm 312.

The third power terminal 31 adopts a material having elasticity greater than that of the fourth power terminal 32. The elasticity of the metal material used for the third power terminal 31 is greater than that of the metal material used for the fourth power terminal 32. The hardness of the metal material used by the fourth power terminal 32 is greater than that of the metal material used by the third power terminal 31. This is because, since the second elastic arm 312 needs to have a certain degree of elasticity, it is beneficial for the third power terminal 31 to be mated with the mating module 200. The second elastic arm 312 can abut against the second extension arm 322 after being deformed. This requires the hardness of the second extension arm 322 to be increased, otherwise the second extension arm 322 is easily deformed.

In the illustrated embodiment of the present disclosure, both the first power terminal 21 and the third power terminal 31 are made of C18150 copper material. The electrical conductivity of the C18150 copper material is 86%. Compared with the pure copper material, reducing the copper content in the C18150 copper material increases its elasticity, which is beneficial to improve the elasticity of the first power terminal 21 and the third power terminal 31. Both the second power terminal 22 and the fourth power terminal 32 are made of pure copper. The electrical conductivity of the pure copper material is 101%. Therefore, both the second power terminal 22 and the fourth power terminal 32 have high conductivity, which is beneficial to improve their current carrying capacity. The pure copper material has weak elasticity and high hardness, which meets the application requirements of the second power terminal 22 and the fourth power terminal 32. Since the conductivity of the C18150 copper material is lower than that of the pure copper material, the conductivity of the second power terminal 22 is better than that of the first power terminal 21, and the conductivity of the fourth power terminal 32 is better than that of the third power terminal 31.

The fourth main body 321 includes a fourth base portion 3211 and a fourth bent portion 3212 bent from the fourth base portion 3211. The fourth tail portion 323 integrally extends from the fourth bent portion 3212. The fourth base portion 3211 is flat. The fourth base portion 3211 is not in contact with the third base portion 3111. Specifically, the fourth base portion 3211 is spaced apart from the third base portion 3111 along the first direction H-H. The fourth bent portion 3212 is spaced apart from the third bent portion 3112. The fourth base portion 3211 is perpendicular to the fourth bent portion 3212. The second extension arm 322 is located on the side of the third surface 311a.

12

After the second terminal module 3 is assembled to the insulating body 1, two sides of the third base portion 3111 are locked in the third slot 181, so as to realize the interference fit between the third power terminal 31 and the insulating body 1, and be beneficial to improve the installation stability of the third power terminal 31. Two sides of the fourth base portion 3211 are locked in the fourth slot 182, so as to realize the interference fit between the fourth power terminal 32 and the insulating body 1, and be beneficial to improve the installation stability of the fourth power terminal 32. The third base portion 3111 is located below the fourth base portion 3211. The fourth base portion 3211 is located below the second base portion 2211. A length of the third base portion 3111 along the third direction L-L is greater than a length of the fourth base portion 3211 along the third direction L-L. A length of the first base portion 2111 along the third direction L-L is greater than a length of the third base portion 3111 along the third direction L-L. The third direction L-L is perpendicular to the first direction H-H. The first direction H-H is perpendicular to the second direction W-W.

Referring to FIG. 18, the second extension arm 322 includes a second connecting portion 3221 extending from the fourth base portion 3211 by bending, and a second contact portion 3222 extending from the second connecting portion 3221. The second contact portion 3222 is configured to be in contact with the second abutting portion 3125. In the illustrated embodiment of the present disclosure, the second contact portion 3222 is in contact with the third base portion 3111. The fourth base portion 3211 is not in contact with the third base portion 3111. The second contact portion 3222 is flat. The second contact portion 3222 is parallel to the third base portion 3111.

In the illustrated embodiment of the present disclosure, referring to FIG. 13, a length of the second inclined portion 2124 along its inclined direction is greater than a length of the first inclined portion 2122 along its inclined direction. An included angle between a surface of the first inclined portion 2122 and the first surface 211a is α_1 . An included angle between a surface of the second inclined portion 2124 and the first surface 211a is β_1 . A numerical value of α_1 is greater than a numerical value of β_1 . A length of the fifth inclined portion 3124 along its inclined direction is greater than a length of the fourth inclined portion 3122 along its inclined direction. An included angle between a surface of the fourth inclined portion 3122 and the third surface 311a is α_2 . An included angle between a surface of the fifth inclined portion 3124 and the third surface 311a is β_2 . A numerical value of α_2 is equal to the numerical value of α_1 . A numerical value of β_2 is equal to the numerical value of β_1 . The numerical value of α_2 is greater than the numerical value of β_2 . When the mating module 200 is inserted into the mating slot 10, the mating module 200 abuts against the first mating portion 2123 and the second mating portion 3123, both the first abutting portion 2125 and the second abutting portion 3125 are subjected to a force in the first direction H-H, and the first abutting portion 2125 and the second abutting portion 3125 receive less force from the first direction H-H. Therefore, the abutting pressure of the first abutting portion 2125 on the second extension arm 322 is reduced, the abutting pressure of the second abutting portion 3125 on the second extension arm 322 is reduced, and the deformation of the first extension arm 222 and the second extension arm 322 is reduced.

In the illustrated embodiment of the present disclosure, referring to FIG. 19, the second elastic arm 312 includes a plurality of second sub-elastic arms 3120 disposed at inter-

vals along the second direction W-W. The second extension arm 322 includes a plurality of second sub-extension arms 3220 disposed at intervals along the second direction W-W. The number of the second sub-elastic arms 3120 is the same as the number of the second sub-extension arms 3220.

The first tail portion 213, the second tail portion 223, the third tail portion 313 and the fourth tail portion 323 are all fixedly connected to a circuit board 300. Referring to FIG. 5, the circuit board 300 defines a first mounting hole 3001, a second mounting hole 3002, a third mounting hole 3003 and a fourth mounting hole 3004. The first tail portion 213 is installed in the first mounting hole 3001; the second tail portion 223 is installed in the second mounting hole 3002; the third tail portion 313 is installed in the third mounting hole 3003; and the fourth tail portion 323 is installed in the fourth mounting hole 3004.

The first mating slot 10a adopts a bell mouth structure. That is, a space of the first mating slot 10a along the first direction H-H gradually expands from inside to outside. This can provide an elastic deformation space for the first power terminal 21 and the third power terminal 31, preventing the insulating body 1 from interfering with the elastic deformation of the first power terminal 21 and the third power terminal 31. Specifically, referring to FIG. 7, the insulating body 1 includes a first slot wall 101 and a second slot wall 102 opposite to the first slot wall 101. The first slot wall 101 and the second slot wall 102 are located on a periphery of the first mating slot 10a. Both the first slot wall 101 and the second slot wall 102 are inclined walls. A distance between the first slot wall 101 and the second slot wall 102 along the first direction H-H gradually increases from inside to outside. From inside to outside refers to an opening from an inside of the first mating slot 10a to an outside of the first mating slot 10a.

Referring to FIG. 22, the third terminal module 4 includes a first signal terminal 41 and a second signal terminal 42. The first signal terminal 41 includes a fifth main body 411, a third elastic arm 412 extending from one end of the fifth main body 411, and a fifth tail portion 413 extending from another end of the fifth main body 411. Part of the fifth main body 411 is accommodated in the third sub-receiving slot 101d. The third elastic arm 412 extends into the second mating slot 10b. The second signal terminal 42 includes a sixth main body 421, a fourth elastic arm 422 extending from one end of the sixth main body 421, and a sixth tail portion 423 extending from another end of the sixth main body 421. Part of the sixth main body 421 is accommodated in the fourth sub-receiving slot 102d. The fourth elastic arm 422 extends into the second mating slot 10b. The third elastic arm 412 and the fourth elastic arm 422 are configured to be in contact with the mating module 200. Both the fifth tail portion 413 and the sixth tail portion 423 are fixedly connected to the circuit board 300. Referring to FIG. 5, the circuit board 300 defines a fifth mounting hole 3005 and a sixth mounting hole 3006. The fifth tail portion 413 is installed in the fifth mounting hole 3005. The sixth tail portion 423 is installed in the sixth mounting hole 3006. Referring to FIG. 5, the insulating body 1 is provided with a positioning post 103, and the circuit board 300 is provided with a positioning hole 3007. The positioning post 103 is installed in the positioning hole 3007 to realize the positioning installation of the insulating body 1 and the circuit board 300.

Compared with the prior art, the first elastic arm 212 in the present disclosure adopts the folded structure. The first elastic arm 212 forms a plurality of elastic deformation points, so that the plugging and unplugging force is dis-

persed, and the plugging and unplugging between the mating module 200 and the first power terminal 21 is relatively soft. After the mating module 200 is plugged in place, the first elastic arm 212 of the first power terminal 21 is in direct contact with the mating module 200; and the first extension arm 222 of the second power terminal 22 is in direct contact with the first elastic arm 212, so that the second power terminal 22 is electrically connected to the mating module 200 indirectly. The first extension arm 222 abuts against the first elastic arm 212, so that the plugging force between the first elastic arm 212 and the mating module 200 can be kept stable.

The above embodiments are only used to illustrate the present disclosure and not to limit the technical solutions described in the present disclosure. The understanding of this specification should be based on those skilled in the art. Descriptions of directions, although they have been described in detail in the above-mentioned embodiments of the present disclosure, those skilled in the art should understand that modifications or equivalent substitutions can still be made to the application, and all technical solutions and improvements that do not depart from the spirit and scope of the application should be covered by the claims of the application.

What is claimed is:

1. A power connector, comprising:
an insulating body defining a mating slot configured to accommodate a mating module; and

a first terminal module assembled to the insulating body, the first terminal module comprising a first power terminal and a second power terminal; the first power terminal comprising a first main body and a first elastic arm bent back from one end of the first main body; the second power terminal comprising a second main body and a first extension arm extending from one end of the second main body; the first elastic arm extending into the mating slot; the first elastic arm being configured to be in contact with the first extension arm when the mating module is inserted in the mating slot;

wherein the first elastic arm is configured to be in direct contact with the mating module; and the first extension arm is configured to be electrically connected to the mating module indirectly through the first elastic arm.

2. The power connector according to claim 1, wherein a first accommodation space is formed between the first main body and the first elastic arm; the first extension arm at least partially extends into the first accommodation space; and when the mating module is not inserted into the mating slot, the first extension arm abuts against the first elastic arm so that the first extension arm is in direct contact with the first elastic arm; or a first gap is formed between the first extension arm and the first elastic arm along a first direction so that the first extension arm is not in contact with the first elastic arm.

3. The power connector according to claim 1, wherein a first accommodation space is formed between the first main body and the first elastic arm; the first extension arm is located outside the first accommodation space and abuts against the first elastic arm.

4. The power connector according to claim 2, wherein the first main body comprises a first base portion and a first bent portion bent from the first base portion; the first elastic arm is formed by bending and extending from the first base portion; and

wherein the first base portion has a first surface and a second surface which are located on opposite sides along a thickness direction of the first base portion;

15

both the first extension arm and the first elastic arm are located on a side where the first surface is located.

5. The power connector according to claim 4, wherein the first elastic arm comprises a first mating portion and a first abutting portion; the first mating portion comprises a first arc-shaped surface; the first abutting portion comprises a second arc-shaped surface; the first arc-shaped surface is configured to be in contact with the mating module; the second arc-shaped surface is configured to be in contact with the first extension arm; the first arc-shaped surface protrudes in a direction away from the first surface; and the second arc-shaped surface protrudes in a direction toward the first surface.

6. The power connector according to claim 5, wherein the first elastic arm comprises a first arc portion, a first inclined portion, a second inclined portion and a third inclined portion; the first arc portion is connected to the first base portion; the first inclined portion is connected to the first arc portion; the first mating portion connects the first inclined portion and the second inclined portion; the first abutting portion connects the second inclined portion and the third inclined portion;

15 a length of the second inclined portion is greater than a length of the first inclined portion; an included angle between a surface of the first inclined portion and the first surface is α_1 , an included angle between a surface of the second inclined portion and the first surface is β_1 , where α_1 is greater than β_1 .

7. The power connector according to claim 5, wherein the second main body comprises a second base portion and a second bent portion bent from the second base portion; the first extension arm comprises a first connecting portion extending from the second base portion by bending and a first contact portion extending from the first connecting portion; and

20 wherein the first contact portion is configured to be in contact with the first abutting portion; and the first contact portion is in contact with the first base portion.

8. The power connector according to claim 1, wherein the first power terminal adopts a material having an elasticity better than that of the second power terminal.

9. The power connector according to claim 7, wherein the mating slot comprises a first mating slot, the first elastic arm extends into the first mating slot, and a space of the first mating slot along the first direction gradually expands from inside to outside.

10. The power connector according to claim 9, wherein the insulating body defines a first receiving slot communicating with the first mating slot; a first locking slot and a second locking slot are provided in the first receiving slot; the first locking slot is configured to hold the first base portion; and the second locking slot is configured to hold the second base portion.

11. A power connector, comprising:
50 an insulating body defining a mating slot configured to accommodate a mating module; and
a first terminal module comprising a first power terminal and a second power terminal; the first power terminal comprising a first main body and a first elastic arm bent back from a front end of the first main body along a front-to-rear direction; the second power terminal comprising a second main body and a first extension arm extending from one end of the second main body along a rear-to-front; the first elastic arm extending into the mating slot; the first extension arm being configured to

16

be sandwiched by the first elastic arm and the first main body when the mating module is inserted in the mating slot;

5 wherein the first elastic arm is configured to be in direct contact with the mating module; and the first extension arm is configured to be electrically connected to the mating module indirectly through the first elastic arm.

10 12. The power connector according to claim 11, wherein a first accommodation space is formed between the first main body and the first elastic arm; the first extension arm at least partially extends into the first accommodation space; and

15 when the mating module is not inserted into the mating slot, the first extension arm abuts against the first elastic arm so that the first extension arm is in direct contact with the first elastic arm; or a first gap is formed between the first extension arm and the first elastic arm along a first direction so that the first extension arm is not in contact with the first elastic arm.

20 13. The power connector according to claim 11, wherein a first accommodation space is formed between the first main body and the first elastic arm; the first extension arm is located outside the first accommodation space and abuts against the first elastic arm.

25 14. The power connector according to claim 12, wherein the first main body comprises a first base portion and a first bent portion bent from the first base portion; the first elastic arm is formed by bending and extending from the first base portion; and

30 35 wherein the first base portion has a first surface and a second surface which are located on opposite sides along a thickness direction of the first base portion; both the first extension arm and the first elastic arm are located on a side where the first surface is located.

40 45 15. The power connector according to claim 14, wherein the first elastic arm comprises a first mating portion and a first abutting portion; the first mating portion comprises a first arc-shaped surface; the first abutting portion comprises a second arc-shaped surface; the first arc-shaped surface is configured to be in contact with the mating module; the second arc-shaped surface is configured to be in contact with the first extension arm; the first arc-shaped surface protrudes in a direction away from the first surface; and the second arc-shaped surface protrudes in a direction toward the first surface.

50 55 16. The power connector according to claim 15, wherein the first elastic arm comprises a first arc portion, a first inclined portion, a second inclined portion and a third inclined portion; the first arc portion is connected to the first base portion; the first inclined portion is connected to the first arc portion; the first mating portion connects the first inclined portion and the second inclined portion; the first abutting portion connects the second inclined portion and the third inclined portion;

60 65 a length of the second inclined portion is greater than a length of the first inclined portion; an included angle between a surface of the first inclined portion and the first surface is α_1 , an included angle between a surface of the second inclined portion and the first surface is β_1 , where α_1 is greater than β_1 .

17. The power connector according to claim 15, wherein the second main body comprises a second base portion and a second bent portion bent from the second base portion; the first extension arm comprises a first connecting portion extending from the second base portion by bending and a first contact portion extending from the first connecting portion; and

wherein the first contact portion is configured to be in contact with the first abutting portion; and the first contact portion is in contact with the first base portion.

18. The power connector according to claim **11**, wherein the first power terminal adopts a material having an elasticity better than that of the second power terminal. 5

19. The power connector according to claim **17**, wherein the mating slot comprises a first mating slot, the first elastic arm extends into the first mating slot, and a space of the first mating slot along the first direction gradually expands from 10 inside to outside.

20. The power connector according to claim **19**, wherein the insulating body defines a first receiving slot communicating with the first mating slot; a first locking slot and a second locking slot are provided in the first receiving slot; 15 the first locking slot is configured to hold the first base portion; and the second locking slot is configured to hold the second base portion.
